J. W. LEAHY, DEC'D.
 M. A. LEAHY, ADMINISTRATRIX
 TRACK CONSTRUCTION.
 APPLICATION FILED OCT. 16, 1907.

946,760.

Patented Jan. 18, 1910.

UNITED STATES PATENT OFFICE.

JAMES W. LEAHY, OF JERSEY CITY, NEW JERSEY; MARY A. LEAHY ADMINISTRATRIX
OF JAMES W. LEAHY, DECEASED.

TRACK CONSTRUCTION.

946,760.

Specification of Letters Patent. Patented Jan. 18, 1910.

Application filed October 16, 1907. Serial No. 397,624.

To all whom it may concern:

Be it known that I, JAMES W. LEAHY, a citizen of the United States, and a resident of Jersey City, in the county of Hudson and State of New Jersey, have invented certain new and useful Improvements in Track Construction, of which the following is a specification.

This invention relates to track construction, and is an improvement of my invention for track construction, described and claimed in my U. S. Patent No. 846,799 dated March 12, 1907.

The distinguishing features of the present invention comprise a tie with shoes in which a supporting block can be fitted to support tracks and with which suspended joints for said tracks can be used.

The invention is specially applicable to concrete track construction:

In the drawings, Figure 1 represents a side elevation of one form of the tie embedded in concrete, Fig. 2 shows a top plan view of Fig. 1, Fig. 3 is a left hand end view of the tie shown in Fig. 1, Fig. 4 represents a partial section of Fig. 2 on the line 4, 4, Fig. 5 represents a plan view of a tie with my invention modified to support a joint of the track on a double end, Fig. 6 shows a partial section of Fig. 5 on the line 6, 6, Fig. 7 is a partial section of Fig. 5 on the line 7, 7, Fig. 8 shows a modification of Fig. 5, and Fig. 9 represents a section of Fig. 8 on the line 9, 9.

Referring to Figs. 1 to 4, a tie is represented with the bottom flange 20, from which extend a pair of shoes, each of which latter is formed with the inclined side walls 22 and the straight wall 23. The walls 23 are located on the opposite sides of the longitudinal axis of the tie. The walls 22 approach each other as they extend from the flange 20, and the wall 23 is perpendicular to said flange. The shoes are connected by the central rib 25 and have extending from their outer inclined walls the ribs 26. The rib 25 has formed therein the openings 28. In each of the shoes is located a bearing block 30 which latter is forced into the shoes so as to tightly fit therein, and project a little above the upper edges thereof. Spikes 31 may be driven through openings in the sides 22 of the shoes into said bearing blocks to hold them in place. A plate 32 is fitted into the top of each block 30 and which

supports the rails 33, by means of screws 34 or spikes. The tie is embedded in a bed of concrete 35.

Referring to Figs. 5, 6 and 7, a tie is shown with a single member 50 at one end and a pair of members 51 at the other end. From the said member 50 extends a shoe with walls 52, 53 similar to 22, 23, and from each of the members 51 extend shoes with walls 54, 55, also similar to 22, 23. The walls 55 are preferably located to face each other as shown. Between the walls 55 and joining the members 51 is formed a pocket 60. In the shoes of this modified tie are located supporting blocks 65, 66, similar to the blocks 30. In the pocket 60 is located a third supporting block 67. A rail 70 is carried on the supporting block 65, and rails 71, 72 are supported on the blocks 66, the abutting ends of the latter rails meeting on the central block 67. The inner wall 52 is connected with the inner walls 54 by the rib 73 having openings 74, and a rib 75 extends from the outer wall 52, while ribs 76 extend from the outer walls 54.

In the modification shown in Figs. 8 and 9 a tie is represented with a single member 80, having a shoe with walls 81, 82, similar to 22, 23 and a supporting block 83 similar to 30. The latter tie at its other end has formed therewith a pair of members 86 connected at their outer ends and provided with shoes having the walls 87, 88 similar to 22, 23 and blocks 89 similar to the blocks 30. The members 86 are connected by an end connection 90. A central rib 91 connects the shoes, and a rib 92 extends from the outer wall 81, while ribs 93 extend from the outer walls 87. Between the walls 88 is formed a pocket 95, over which extend the ends of the rails 96, 97 that are carried on the blocks 89. The latter disposition of parts allows the introduction of the suspended joint for the rails as shown, or a block 100 may also be located in the pocket 95 to bear up against the rails. A wedge 100 may be forced between the supporting blocks and the flange of the tie, to hold said blocks securely in place. The ties are preferably made of cast metal, and the blocks are preferably made of wood.

The ties when used in a track construction are placed practically parallel to each other, and support rails on their supporting blocks,

avoiding the use of longitudinal stringers to support said rails.

Although concrete is shown with the tie in Fig. 1, ballast may be substituted therefor, and either concrete or ballast may be used for any of the forms of ties represented. The openings in the ribs like 28, allow the concrete or ballast to bind the tie in place.

Having described my invention I claim:

- 10 1. In a metal tie for track construction, the combination of an upright wall extending lengthwise of the tie and two upwardly converging transverse walls forming a shoe, a wood bearing block secured in the shoe and projecting above its walls, and a plate embedded in the top of said block to receive the rail.
- 20 2. A tie for track construction comprising a casting having a single integral shoe at one end and a pair of separate aligned integral shoes at the other end, and rail supporting blocks in said shoes.
- 25 3. A tie for track construction comprising a casting having a single member at one end and a pair of members at the other end, a bottom flange connecting said members, and a branched rib on said flange connecting said single member with each of the other members.
- 30 4. A tie for track construction comprising a casting having a single integral shoe at one end and a pair of integral shoes at the other end, a branched rib connecting the single shoe with each of the other shoes, and rail supporting blocks in said shoes.
- 35 5. A tie for track construction comprising a casting having a single integral shoe at one end and a pair of separate aligned integral shoes at the other end, rail sup-

porting blocks in said shoes, and an integral connection between the single shoe and each of the other shoes.

6. A tie for track construction consisting of a single casting comprising a single member at one end and a pair of members at the other end, a bottom flange beneath said members, and a connection between the flanges beneath said pair of members.

7. In a tie for track construction the combination of a single member at one end of the tie, a pair of members at the other end thereof, a shoe formed with each member, a supporting block located in each shoe, and a pocket connecting the shoes of the double member.

8. In a tie for track construction the combination of a single member at one end of the tie, a pair of members at the other end thereof, a shoe formed with each member, a supporting block located in each shoe, a pocket connecting the shoes of the double member, and a block located in said pocket, a rail on the block of the single member, and rails on the blocks of the double member, the block in the pocket supporting abutting ends of the latter rails.

9. In a tie the combination of a flange, a shoe at each end of the flange, supporting blocks in the shoes, and a wedge bearing between each block and flange to hold the block in place in its shoe.

Signed at the borough of Manhattan in the county of New York and State of New York this 12th day of October A. D. 1907.

JAMES W. LEAHY.
